SPLICED LUMBER

Harry C. Graham, Pittsburgh, Pa., assignor to
Pittsburgh Screw & Bolt Company, Pittsburgh,
Pa., a corporation of Pennsylvania

Application March 16, 1944, Serial No. 526,693

1 Claim. (Cl. 20—91)

1

This invention relates to the splicing of lumber and to a method of splicing the same, and provides a method whereby lumber may be spliced to resist separation under mechanical strains, vibration and varying weather or moisture conditions.

The present invention is based on the recognition of the fact that high grade lumber, particularly in the larger and longer sizes, is becoming increasingly scarce, expensive, and difficult to secure. Long lengths of heavy timber for use in piling, for example, are very difficult to secure and quite expensive. Likewise, long lengths of heavy timber for use in building or other constructions, are also difficult to procure. On the other hand, increased recognition is being given to the use of wood in various construction operations, where heretofore reinforced concrete has been employed, due to the fact that for many types of work, particularly where exposed to rigorous climatic conditions and mechanical vibration, concrete has been found to spall, crack, or disintegrate. For example, in railway station platforms and railway grade crossings, there is an increasing demand for wood, not only because of the greater service which it will render, but the ease with which it may be taken up and replaced for access to the track or other purposes. Likewise there is an increased demand for timber in lieu of concrete for highway and other bridges.

The present invention provides for the economical splicing together of smaller pieces of lumber into a composite whole which not only enables large or heavy timbers to be constructed, but enables in many cases, inferior grades of lumber to be very successfully employed, and the use of the present invention constitutes a factor in the conservation of valuable timber.

It has heretofore been proposed to join smaller pieces of lumber together by spikes or by nails, but this is not adequate due to the fact that the nails are incapable of holding the wood together, especially after a period of time has elapsed and the lumber has become exposed to frequent alternate periods of wetness and dryness. More especially is this true in places where considerable vibration is encountered, as for example in station platforms, bridges, and the like. Attempts have been made also to accomplish the result by the use of bolts and nuts, but here again difficulty has been encountered, due to the fact that the weaving or vibration of the wood tends to enlarge the hole through which the bolt passes, while shrinkage of the wood often allows the tension under which the bolt is initially

placed to be relieved, this latter result increasing the weaving or relative movement between the joined pieces, permitting the bolts to become increasingly loose. Not only is this the case, but under conditions of continued service, the nuts will actually move under vibration to a point where they drop completely off the bolt. As soon as any fastener becomes loose in the wood, the initial bond between the fastener and the wood quickly disintegrates, and the wood actually seems to recede from the fastener. Experience has demonstrated therefore, that usual types of fastenings fall down and are unsatisfactory in many instances where these conventional fasteners would be expected to be satisfactory.

According to the present invention, pieces of lumber are successfully spliced for service over many years of time. In the practice of the present invention, the two or more pieces of wood which are to be joined are temporarily secured or clamped together. Then they are drilled with a hole extending through one piece and at least part way, if not entirely through the other. A dowel is then entered in this hole, the dowel having coarse spiraled fins or threads thereon, the angular pitch of which is not more than 45° to the longitudinal axis, or is greater than 45° to a plane passing transversely through the dowel. This pitch is such as to cause the dowel to be rotated as it is driven into the hole, the diameter of the hole being approximately the same, and preferably no greater than the root diameter of the dowel. By reason of this, the dowel completely fills the hole and the spiral threads or vanes compress the surrounding portions of the wood as they cut a steeply spiraled thread into the wood. The dowel is of a length such as to extend completely through the piece into which it is first entered and penetrate a substantial distance into or entirely through the second piece, or succeeding pieces. After the pieces have been doweled in this manner, the clamps if employed are released and the pieces will be permanently held. One important factor contributing to the success of this means of securing the pieces together arises from the fact that in driving the dowel it is impossible to strip the threads because each inward thrust of the dowel under the blow of a hammer produces a proper amount of rotation and it is impossible to rotate the dowel without causing it to penetrate further into the wood. Another factor is that the threads in the wood, being inter-fitted with the threads on the dowel, have an angular pitch more nearly approximating longi-

tudinal keys than a succession of threads as is provided by ordinary wood screws or lag screws. This keying action serves to effectively resist the turning of the dowel except when accomplished by a driving force. In other words, the dowel cannot be turned as a screw is turned. Finally, a very important factor in the success of the present method is that due to the fact that when such a dowel is driven into wood, relative movement between the wood and the dowel tends to rotate the dowel. Therefore any force tending to move two doweled pieces apart tends to rotate the dowel, and since in separating, the two pieces move in opposite directions, each would exert an opposite turning force on the dowel; i. e., one of the two pieces would tend to rotate the dowel in a clockwise direction, while the other would tend to rotate it in a counter-clockwise direction, with the result that the forces would be neutralized and the turning could not occur.

My invention may be more fully understood by reference to the accompanying drawings, in which:

Fig. 1 is a side elevation of a dowel designed for use in the present invention;

Fig. 2 is a transverse section in the plane of line II—II of Fig. 1;

Fig. 3 is a more or less schematic view illustrating the manner in which the pieces are prepared for splicing;

Fig. 4 is a longitudinal section through two pieces of lumber joined in end to end relation, in accordance with the present invention;

Fig. 5 is a top plan view of another assembly, such as a floor panel embodying my invention, useful for bridge floors, boardwalks, station platforms, grade crossings, and elsewhere where a wooden floor of this character is desirable;

Fig. 6 is a transverse section in the plane of line VI—VI of Fig. 5, this view being on a larger scale;

Fig. 7 is a view partly in side elevation and partly in section of still another form of structure embodying my invention;

Fig. 8 is a schematic view illustrating the resolution of forces created in the dowel when the pieces tend to separate, the view being purely a schematic view; and

Fig. 9 is a view similar to Fig. 5 of a slightly modified form of panel.

Referring first to Figs. 1 and 2, the dowel comprises, in its preferred embodiment, merely a length of rod having a plurality of steeply spiraled threads thereon. In Fig. 1, 2 designates the dowel and 3 designates the threads. The threads form an angle of 45° or more to a vertical plane passing through the dowel. This steep pitch of the threads causes the dowel to rotate when it is being driven into the wood and the pitch is so steep that the threads will not serve to draw the dowel into the wood when the dowel is turned in the manner of an ordinary wood screw. The threads may be formed on the dowel either by rolling or by twisting a rod of non-circular cross section about its own axis. The dowel per se is well known to those skilled in the art, and alone forms no part of the present invention.

According to the present invention, as illustrated in Fig. 3, the two or more pieces to be joined together are temporarily secured or clamped. In Fig. 3, 4 designates one of two pieces and 5 designates the other. They are held in any conventional vice-like or other clamp 6. After being clamped, one or more, preferably a plurality of spaced holes 7 are drilled therein, the holes

passing entirely through one of the pieces, and either entirely or partially through the other piece or pieces. In Fig. 3 the hole is shown as extending entirely through the two pieces. It is merely necessary, however, that it extend through one piece and well into the other. The hole 1 has a diameter which is preferably equal to the root diameter of the dowel 2.

The dowels are then driven into the several holes 7, being hammered in with a sledge or otherwise forced in under impact or pressure. As they travel along the hole, they rotate, cutting a steeply spiraled thread into the wood. The wood immediately around the hole is compressed and is forced into intimate contact with the surface of the dowel between the threads so that an initially tight hold is established between the wood and the dowel.

After the dowels have been driven, the clamp or other holding means 6 may be released, whereupon the parts will be firmly united. As hereinbefore indicated, when they are so united, forces which tend to cause other forms of fasteners to become loose appear to have no effect. As shown in Fig. 8, the two pieces which are joined together are designated A and B. Forces tending to spread them in opposite directions as indicated by the straight arrows tend to rotate the dowel. The circular arrows indicate that these forces being exerted in opposite directions tend to rotate the dowel in opposite directions. The result is that the dowel cannot rotate, wherefore the pieces cannot spread apart. In no other condition of spike or screw is this result obtained. Repeated swelling and shrinking of the wood therefore has no effect, and test installations have established the permanence of a splice or joint thus made.

In the present invention, the term "spliced" is intended to include either the piecing of elements together in end to end relation, or in face to face relation. Fig. 4 illustrates one practical application of my invention as applied for example to lengths of heavy timber to be used for piling, or elsewhere where heavy timber is required. Prior to the present invention, it has been proposed to lap the ends of the pieces, bolt them together, and then span the joint with an annular series of stays or braces extending longitudinally of the assembly. With the present invention, much more permanent and satisfactory results are obtained, and it is unnecessary to use the external stays or connectors.

In Fig. 4, 10 designates the upper of two members, and 11 is the lower one. As shown, the members have the ends thereof cut away to form overlapping tongues 10a and 11a respectively. These overlapping portions are firmly held in abutting and face to face relation and drilled as described in connection with Fig. 3, and the dowels designated 12 are then driven. Preferably they are driven from opposite directions so as to secure even more effective holding power.

In Figs. 5 and 6, there is illustrated a prefabricated construction panel designed for use in station platforms, crossings, boardwalks, bridge floors, or elsewhere where such construction is applicable. It may be assembled in many cases, from inferior or cheaper grades of lumber. A typical panel, for example, may be made from pieces of 2 x 4 set edgewise and secured in the manner hereinafter described, these pieces being either of uniform length or being of short length. In Fig. 5, 15 designates each of the several pieces, and as indicated at 15a, the full length of some of the pieces may be less than the total length of the

5

panels so that some of the pieces are butted in end to end relation.

In making up the panels, a plurality, as for example 3 pieces 15, are first clamped together and dowels 16 are entered into them, these dowels being the dowels illustrated in Fig. 1. In Fig. 1 they are illustrated as being entered from the left toward the right. The dowels are inserted by first drilling through the several pieces in the manner hereinbefore described. After the first three pieces have been secured, two more additional pieces may be clamped to the assembly, to the left-hand side thereof, and the dowels 16' are entered, after first drilling the pieces. These dowels extend not only through the two pieces which have been additionally added, but extend into that piece marked 15b, this being the innermost of the first group of pieces. After these pieces have been doweled, two more pieces are again applied, drilled and doweled, the dowels 16" passing through these two pieces and into the piece marked 15c. In this manner the panel is built up to any desired convenient width by adding additional pieces to the left-hand side of the panel. I have described the starting of the panel with three pieces followed by the addition of multiples of two, but this is purely arbitrary. It is necessary, however, to stagger the dowels as illustrated, both longitudinally and transversely in order that one dowel will not be driven into another, and in order to develop maximum strength. These panels are prefabricated at an appropriate assembling plant from which they are sent out into the field. In a structure such as that shown in Figs. 5 and 6, it is especially desirable to use dowels that do not have heads, in order that several pieces may be arranged in face to face contact.

In Fig. 7 there is illustrated another form of prefabricated structural unit useful for example in the construction of guard rails on highway bridges, or elsewhere where uprights are required. Whereas usual practice would require the use of integral posts for this purpose, stronger and cheaper posts which incidentally may also be more artistic, are provided by the present invention. In Fig. 7 the post is illustrated as being composed of several pieces of lumber 20, 21, and 22, which are illustrated as being of different lengths, but which may be of the same length. The lower ends of the several members terminate in a common plane whereas the upper ends are stepped to improve the appearance of the unit. The several pieces are doweled in the manner hereinbefore described, the dowels being indicated at 23. These posts are previously prepared in a fabricating plant. They cannot be separated as they could if ordinary nails or spikes were used. No bolts are required, and the dowels will hold the pieces more satisfactorily than would bolts for the reason that the dowels will not become loose in the wood. Additionally, as shown in Fig. 7 the composite post as thus constructed may be held by dowels 24 to a horizontally extending timber 25 forming a part of the bridge.

6

In Fig. 9 there is disclosed a prefabricated structural panel similar to Fig. 5, but in which the dowels, 30, are of a length to extend continuously through all of the individual strips 31. In either the form shown in Fig. 5 or Fig. 9, the dowels are close enough and heavy enough to provide load distributing bars to transmit and distribute heavy wheel loads for example over a considerable area.

While I am aware that it has heretofore been proposed to splice or secure the pieces of wood together for extending the length or width thereof, and while I am also aware that dowels having only spiraled threads such as to enable them to be driven have heretofore been used in other fields, it has not heretofore been recognized that the use of these dowels for the splicing or joining of pieces of wood to form a structural unit would provide such a structural unit capable of standing up under extremes of weather and service condition over long periods of time without requiring attention, and wherein the parts cannot separate. In other words, my invention enables small pieces of lumber to be integrated into structural units which in turn may be employed in places where only expensive timber could heretofore be used, or enables timber to be used in locations where heretofore it would not be serviceable.

I claim as my invention:

A prefabricated wooden construction unit comprising a plurality of side-by-side rows of pieces of lumber of varying lengths, which pieces are arranged in end-to-end relationship in said rows, said unit having a plurality of holes extending transversely therethrough and spaced longitudinally thereof, a plurality of driven metallic screw threaded dowels extending through said holes, the diameter of said holes being approximately equal to the root diameter of said dowels, the threads of said dowels having sufficient steepness of pitch so as to cause rotation of said dowels when driven through said holes.
